UNITED STATES PATENT OFFICE

103,053

DESIGN FOR A SHOE

Albert W. Lutz, Brockton, Mass., assignor to Geo. E. Keith Company, Campello, Mass., a corporation of Massachusetts

Application December 3, 1936, Serial No. 66,293

Term of patent 3½ years

To all whom it may concern:

Be it known that I, Albert W. Lutz, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side elevation of the same.

Both sides of the shoe present substantially the same appearance.

The essential feature of the invention resides in the arrangement and combination of rows of stitching and punched holes in the material of which the vamp and quarter of the shoe are made. As the design is applicable to shoes of various shapes and styles the representation of shoe is merely conventional, for showing an application of the design.

I claim:

The ornamental design for a shoe, as shown and described.

ALBERT W. LUTZ.
